[57] CLAIM

The ornamental design for a rocking chair, as shown and described.

DESCRIPTION

FIG. 1 is a top perspective view of a rocking chair showing my new design in the form of a children's chair;

FIG. 2 is a right side elevational view thereof;

FIG. 3 is a left side elevational view thereof;

FIG. 4 is a top plan view thereof;

FIG. 5 is a front elevational view thereof;

FIG. 6 is a rear elevational view thereof;

FIG. 7 is a bottom plan view thereof;

FIG. 8 is a top perspective view of a rocking chair showing a second embodiment of my design in the form of an adult's chair;

FIG. 9 is a right side elevational view of the second embodiment thereof;

FIG. 10 is a left side elevational view of the second embodiment thereof;

FIG. 11 is a front elevational view of the second embodiment thereof;

FIG. 12 is a rear elevational view of the second embodiment thereof;

FIG. 13 is a top plan view of the second embodiment thereof;

FIG. 14 is a bottom plan view of the second embodiment thereof; and

FIG. 15 is a top perspective view showing a third embodiment of my design in the form of a dual rocking chair for children.
